CLAIM

The ornamental design for a "illuminated safety harness," as shown and described.

DESCRIPTION

FIG. 1 is a perspective view of an illuminated safety harness showing my new design;

FIG. 2 is front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken line portion of the figure drawings is included to show unclaimed subject matter and illustrate the environment of the design only, and forms no part of the claimed design.
